corporation of New York

Application May 24, 1930. Serial No. 455,377

5 Claims. (Cl. 83—73)

The present invention relates to apparatus for transporting ready mixed concrete from a central mixing plant at the points where construction operations are being conducted. More specifically, the present invention relates to apparatus which is adapted to carry out the process described and claimed in my copending application Serial No. 262,789. The present application also embodies some features of apparatus disclosed in my copending applications Serial No. 214,995 and Serial No. 326,395.

The objects of the present invention and the advantages that flow therefrom will be apparent to those skilled in the art from the following specification and the drawings which constitute a part of the present application.

In the drawings:

Fig. 1 is a view in side elevation of a motor truck illustrating a concrete conveying and mixing tank constructed in accordance with the present invention mounted thereon, the said tank being illustrated in raised or discharge position.

Fig. 2 is an enlarged view in side elevation of the conveying tank and supporting chassis or frame therefor.

Fig. 3 is a transverse detail sectional view through the tank chassis, taken on the line 3—3 of Fig. 2.

Fig. 4 is a further enlarged view in front elevation of the conveying tank, illustrating more particularly the rotating mechanism associated therewith.

Fig. 5 is a view in rear elevation of the concrete conveying tank.

Fig. 6 is a fragmentary detail view similar to Fig. 5, more particularly illustrating the concrete discharge door, parts being omitted.

Fig. 7 is a detail sectional view taken on the line 7—7 of Fig. 4.

Fig. 8 is a detail sectional view taken on the line 8—8 of Fig. 4, illustrating the pillow block comprising a support or bearing for the conveying tank.

Fig. 9 is a detail sectional view taken on the line 9—9 of Fig. 6 illustrating the rear or discharge end of the tank.

Fig. 10 is a detail sectional view taken on the line 10—10 of Fig. 6.

Fig. 11 is a detail sectional view taken on the line 11—11 of Fig. 6.

Fig. 12 is a detail top plan view of the chassis or frame for supporting the conveying tank, illustrating the same detached.

Fig. 13 is a detail view in side elevation of the said supporting chassis.

Fig. 14 is a detail view in end elevation of the said supporting chassis, also illustrating the same detached.

Fig. 15 is a view in side elevation of a motor truck having a concrete conveying and mixing tank mounted thereon, illustrating a modified form of hoist, the said tank being illustrated in raised or discharge position.

Fig. 16 is an enlarged detail fragmentary view illustrating the supporting arms or hoist for raising the tank to discharge position.

Fig. 17 is a detail transverse sectional view taken on the line 17—17 of Fig. 16.

Figs. 18, 19, 20, and 21 are enlarged detail views illustrating the several points of connections of the hoisting arms.

One form of the invention is illustrated in Fig. 1 and comprises a truck 22 having a body frame 23 and a rotatable tank 24 which carries the premixed concrete. The rotatable tank 24 is provided with a pair of trunnions 25 which are supported by the cooperating pair of trunnion bearings 26 and 27, these in turn being carried by supports 28, 29, respectively. This entire organization is supported by a tiltable frame 30 which is pivoted at a point 31 substantially coincident with the rear end of the tank 24 to the rear end of the main body frame 23. The tiltable frame 30 which, as shown, is disposed below the tank 24 and is interposed between the main body frame 23 and the tank 24, also carries the power device such as an internal combustion engine 32 for rotating the tank 24. The truck 22 is provided with a hoisting device well known in the art which is schematically illustrated in Fig. 1 by the element 33 for raising the tank from its horizontal position to its tilted position.

The above in brief illustrates the main co-operating elements in the present construction. The detailed description of various parts of the organization will now be taken up individually.

The construction of the tiltable frame 30 and its associated supporting elements 28 and 29 is shown in greater detail in Figs. 2, 3, 12, 13 and 14. The tiltable frame 30 is best illustrated in Figs. 12 and 13. A pair of longitudinally disposed I-beams 34 are shown, the same being provided with a reinforcing transverse member 35.

At the rear end thereof the frame is provided with a transverse member 36 which is disposed across the rear ends of the I-beams 34. A pair of plates 37 are carried at the rear end of the frame, these plates being inclined toward each other.

other and being bridged by a horizontal plate 38 which serves as a table for supporting the rear trunnion bearing 26. The plates 37 together with the table 38 constitute a frame for the outlet of the tank 24 so that when the tank is tilted to the position shown in Fig. 1 and the sliding door 39 is opened the concrete may be observed as it passes or flows out of the tank.

Associated with the frame 30 at this point is a chute 40 pivoted on the frame 30 and extends downwardly and rearwardly between the longitudinal beams 34 and may be adjusted to various raised or lower positions by means of the chain 41. Lugs or ears 42 are provided at the sides 10 of the chute 40 near the discharge end to hang the supporting hooks of a longer additional chute thereon when desired. When the rotation of the tank is stopped preparatory to raising it and to removing its contents, care is taken that the 15 position of the tank is such that the outlet of the tank is disposed between the legs 37 of the table 38 so that the contents of the tank flow out into the chute 40 and are directed properly. The frame 30 preferably carries the laterally 20 disposed tables 43. The forward portion of the frame 30 is also provided with a table 38' for the support of the forward trunnion bearing 27; this table 38' being similarly supported by a pair of legs 37' which are bolted onto the I-beams of 25 the frame 30.

In addition to the trunnion bearing table, the front portion of the frame also is provided with a table 43 for the support of the power device 32.

Referring now to the specific construction of 30 the tank 24 and of the means for supporting and rotating the same, it is important to note that the tank is provided with a smooth unencumbered interior, the tank being substantially cylindrical in shape and having no stirring or agitating device disposed interiorly thereof. The present apparatus being designed for the purpose of carrying out the process disclosed in my copending application Serial No. 262,789, is provided with a power device 32 for rotating the tank at a slow 35 rate so that the concrete which is in a wet, flowable condition will be subjected to a slow rolling over motion thereby permitting the air entrained within the concrete during the process of mixing to escape therefrom to the space available above 40 the body of concrete. In order to accomplish this purpose the tank is provided with smooth interior walls, and is provided with trunnions 25 which are clearly illustrated in Fig. 8 of the drawings. The use of these trunnions obviates 45 the use of any shaft interiorly of the tank thus permitting the loading of the tank up to almost three-fourths of its height and still permitting the slow rotation of the tank and subjecting the concrete to the slow rolling over motion without 50 the body of concrete meeting any obstructions whatever.

Referring to Fig. 8, the trunnion 50 will be observed as being provided with a head plate 51, which is bolted against the end plate 52 and held 55 in place by means of the trunnion flange 53 which is disposed exteriorly of the tank. The trunnion 52 is provided with the reduced portion 54 which carries the pillow block 55 supported on the table 38.

Before attaching the trunnion 50 and the trunnion flange 53 to the tank head 52, the tank head is stiffened by attaching thereto a stiffening annular plate 55 on the inside of the tank head 52 and surrounding the opening through which the trunnion 50 passes. This plate 55 is prefera-

bly attached to the tank head 52 by welding the same around its periphery 56 to the inside of the tank head. The bolts 57 and 58 serve to hold the trunnion, and the trunnion flange in assembled relation to the tank head 52 and the stiffening plate 55. The bolts 58, disposed on the lower portion of this assembly are preferably countersunk so as not to interfere with the sliding of the rear or discharge door or gate 59. The trunnion flange 53 is provided with a series of reinforcing ribs 60. It will be seen, however, that the lower portion of the flange 53 does not have any rib which would interfere with the movement of the sliding outlet door or gate 59.

The construction and manner of securing the forward trunnion 25 will be understood, there being many modifications which flow out of the fact that the forward trunnion is shorter than the rear trunnion with the result that the trunnion flange need not be reinforced in the manner shown in flange 53.

The rear trunnion is substantially longer than the forward trunnion by reason of the fact that room must be provided between the table 38 and the tank head for the operation and manipulation 100 of the sliding door 59. It will be seen, therefore, that the entire table construction as supporting the forward trunnion bearing 27 is spaced much more closely with relation to the forward tank head than the rear trunnion bearing and its table. 105

The trunnion bearings which are duplicated, one being provided to cooperate with each trunnion, are shown in detail in Fig. 8. The housing 61 is held on the table 38 by means of bolts 62 shown in Fig. 5. Mounted within the housing 61 110 is the anti-friction roller bearing assembly 62. The inner rotatable member 63 of this assembly rotates with the reduced portion 54 of the trunnion. The end collars 64 serve to clamp these elements and hold the same in their assembled 115 relation. The end closure cap 65 shown in Fig. 5 is secured to the housing and makes an oil tight joint therewith. The type of bearing shown herein is provided with two sets of anti-friction rollers 66 disposed angularly with relation to each 120 other as shown in Fig. 8. By means of this type of bearing the end thrust is taken up by each of the bearings at each end of the tank. This is important when it is realized that an apparatus of the type described herein frequently carries 125 several tons of concrete in a liquid flowable condition. Sudden application of brakes to the entire truck causes a very considerable end thrust upon the entire tank. These bearings are designed to 130 co-operate with the entire apparatus so as to completely take up all end thrust of the tank and its contents in either direction.

Referring now to the specific construction of the outlet and sliding door, the same is illustrated in Figs. 5, 6 and 10. The rear tank head 52 is provided with a discharge opening 67 more clearly illustrated in Fig. 9. An inspection of Fig. 9 will show that the rear tank head 52 which is provided with an interiorly extending flange 68 has the opening 67 disposed over the lower portion so that the main cylindrical portion of the tank 24 constitutes the bottom of the outlet opening 67 whereas the sides and top of the opening are within the tank head 52. In order to stiffen the tank head 52 and prevent any possible injury thereto at the top of the opening 67, the reinforcing angle iron 69 is disposed immediately above the opening 67 interiorly of the tank. The angle plate 69 is preferably welded onto the adjacent 145 portions of the tank and if desired the ends there- 150

of may be covered by plates welded or otherwise attached thereto to prevent the lodgment of any concrete between this angle plate 69 and the tank wall 52.

5 In order to protect the bottom of the opening 67 against any possible injury the arcuate bar 70 is riveted onto the outer edge of the tank 24 which constitutes the bottom of the opening 67. This bar 70 preferably extends substantially beyond the outer edge 71 of this portion of the tank and serves as part of the frame work for the opening 67 and the sliding door 59. At its opposite ends the reinforcing bar 70 is welded to the tank head 52 as shown at 72 in Fig. 11.

15 A door frame 73 having a shape similar to the shape of the outlet 67 is attached to the end wall of the tank by screws or the like. Mounted on the door frame and along each side of the opening are the angle bars 74 which provide tapering passages with the vertical portions of the frame 73 for the operation of the sliding door 75. The specific construction and operation of this door is clearly illustrated in my copending application Serial No. 326,395, and a further description of this portion of the disclosure is therefore unnecessary herein.

20 The tank 24 is provided with a ring gear 80 which is made integral with the external face of the tank 24 preferably at the forward end thereof. The tank 24 is thus rotated by the engagement of pinion 81 with the above mentioned ring gear 80. The pinion 81 is mounted on the pinion shaft 82 which is connected to the source of power 32 and operated thereby. The ring gear is preferably covered by the channel shaped guard 83, this guard being supported by braces 84 and 85, these braces also serving as reinforcing elements for the lateral tables 42.

25 The pinion shaft 82 is preferably connected to the source of power 32 by means of a sprocket 86 driven by a chain operated by the motor 32. The pinion shaft 82 is also provided with a brake mechanism 87 which may be operated by the manual member 88. The manual lever 89 also operates a clutch mechanism between the source of power 32 and the pinion shaft 82.

30 When it is desired to fill the tank with pre-mixed concrete, the tank may be brought to its proper position with its filling opening 90 properly disposed with relation to the incoming concrete and the hand brake lever 88 may be operated to hold the tank in this position. When the tank has been filled to approximately three-fourths its height the door is closed and latched. 35 The brake lever 88 is then released and the clutch lever 89 is operated to bring the motor 32 into operable relation with the pinion shaft 82. By means of this apparatus the tank 24 is rotated slowly and continuously during the transportation of the concrete from the central plant to the point where the building operations are conducted. The shell of the tank is smooth-walled, there being no paddles, blades or vanes or any agitating devices within the tank. When the tank is brought to its destination and it is desired to remove the contents of the tank, the motor 32 is disengaged from the tank and the brake mechanism 87 is utilized to bring the tank 40 to a full stop at the point where its outlet 67 is properly positioned by means of the hoisting apparatus schematically illustrated by reference character 33 in the drawings, the tank being brought into the position shown in Fig. 1. The sliding door is then moved to its open position

and the concrete flows out of the tank along chute 40.

45 The engine 32 is preferably set at such a speed that the tank 24 will rotate at from eight to twelve revolutions per minute. This operation of the tank combined with the fact that the interior of the tank is entirely nonobstructed, subjects the wet, flowable concrete within the tank to a slow rolling over motion which has the effect of releasing all air entrained within the concrete during the violent agitation to which it is subjected during the mixing of the raw materials. In addition, therefore, to preventing stratification and setting of the concrete the present apparatus also subjects the concrete to a conditioning treatment which causes the expulsion of the entrained air in the concrete and thereby greatly improves its quality.

50 The construction illustrated in Fig. 2 of the drawings constitutes a unit which may be mounted on a motor truck for transporting the same or if desired it may be mounted on an industrial car for travel on rails. While it is preferred that the vehicle which transports the unit shown in Fig. 2 should be provided with a hoisting mechanism to tilt the entire unit to its discharge position, it is obvious that if desired the unit may be discharged with the aid of any hoisting mechanism. By opening the discharge door most of the contents of the tank will flow out and the remainder may be scraped out by any suitable implement.

55 In the apparatus shown in Fig. 15, the same unit illustrated in Fig. 2 of the drawings is mounted in such a manner that it may be hoisted to a much higher level as shown. For this purpose it is not necessary to modify the construction of the unit which comprises the tiltable frame, the tank and the operating device for the tank which are also carried by the frame. Neither is it necessary to modify the construction of the truck or the truck frame. It is merely necessary to insert between the tiltable frame and the body frame of the truck the apparatus

50 shown in Figs. 15 to 21, which provide for raising the tank to the higher level indicated. This apparatus comprises one pair of arms 100 which are pivoted at their upper ends to the frame members 34 at the points 101 and provided with means at the lower end to slide within the channel of the channel members 104. These means are clearly shown in Fig. 20 which shows the lower end of the member 100 provided with a roller 102 which travels within the channel of the member 104. A cross member 115 is carried by the members 100 at their lower ends as shown in Figs. 17 and 20. Another pair of members 103 are pivoted at their lower ends to the pivot points 105 which are carried by the rear end of the body frame and are provided with means at their upper ends for sliding with relation to the tiltable frame members 34. These means are shown in Fig. 18. The member 103 is provided with a yoke 106 which carries a stud shaft 107, the latter being provided with a rotatable roller 108 which engages against the lower face of the member 34. The stud shaft 107 also carries an angle bracket 109 which rides over the upper face of the bottom 110 of the channel member 34.

55 Each pair of corresponding elements 100 and 103 are pivoted to each other as shown in Fig. 19 at 111. These means are clearly shown in Fig. 21 which shows the lower end of the member 100 provided with a roller 102 which travels within the channel of the member 104. A cross member 115 is carried by the members 100 at their lower ends as shown in Figs. 17 and 20. Another pair of members 103 are pivoted at their lower ends to the pivot points 105 which are carried by the rear end of the body frame and are provided with means at their upper ends for sliding with relation to the tiltable frame members 34. These means are shown in Fig. 18. The member 103 is provided with a yoke 106 which carries a stud shaft 107, the latter being provided with a rotatable roller 108 which engages against the lower face of the member 34. The stud shaft 107 also carries an angle bracket 109 which rides over the upper face of the bottom 110 of the channel member 34.

60 Each pair of corresponding elements 100 and 103 are pivoted to each other as shown in Fig. 19 at 111. These means are clearly shown in Fig. 21 which shows the lower end of the member 100 provided with a roller 102 which travels within the channel of the member 104. A cross member 115 is carried by the members 100 at their lower ends as shown in Figs. 17 and 20. Another pair of members 103 are pivoted at their lower ends to the pivot points 105 which are carried by the rear end of the body frame and are provided with means at their upper ends for sliding with relation to the tiltable frame members 34. These means are shown in Fig. 18. The member 103 is provided with a yoke 106 which carries a stud shaft 107, the latter being provided with a rotatable roller 108 which engages against the lower face of the member 34. The stud shaft 107 also carries an angle bracket 109 which rides over the upper face of the bottom 110 of the channel member 34.

65 Each pair of corresponding elements 100 and 103 are pivoted to each other as shown in Fig. 19 at 111. These means are clearly shown in Fig. 21 which shows the lower end of the member 100 provided with a roller 102 which travels within the channel of the member 104. A cross member 115 is carried by the members 100 at their lower ends as shown in Figs. 17 and 20. Another pair of members 103 are pivoted at their lower ends to the pivot points 105 which are carried by the rear end of the body frame and are provided with means at their upper ends for sliding with relation to the tiltable frame members 34. These means are shown in Fig. 18. The member 103 is provided with a yoke 106 which carries a stud shaft 107, the latter being provided with a rotatable roller 108 which engages against the lower face of the member 34. The stud shaft 107 also carries an angle bracket 109 which rides over the upper face of the bottom 110 of the channel member 34.

70 The hoisting device 112 engages the cross bar 113 which is disposed between the members 103. It will be seen from the above that when the

hoisting device 112 is operated the tank may be raised from its normal position to the position shown in Figs. 15 and 16 and that during this operation the upper end of members 103 will travel in the channel members 34 and the lower end of members 100 will travel in the channel members 104 and in the collapsed condition the rear end of the tank will coincide approximately with the rear end of the frame 104 and will overlie the pivot point 105.

The present invention therefore comprises a unit which consists of a frame 34 which supports a rotatable tank and also supports a source of power for rotating the tank. The frame also supports control mechanism such as a clutch or a brake for controlling the rotation of the tank. This entire unit may be mounted on a truck as shown in Fig. 1 so that the same is pivoted with relation to the truck and may be tilted by means 20 of the hoisting mechanism to the slanting position shown in Fig. 1. The same unit, however, may be mounted as shown in Figs. 15 and 16, so that it may be raised to a much higher level and tilted to its slanting position at the same time.

One of the advantages that flow from the apparatus disclosed herein resides in the fact that the unit shown in Fig. 2 of the drawings, or if desired that unit combined with the elements 100 and 103, is interchangeable with a standard dump body. In other words, a truck carrying the standard dump body may be utilized also for carrying the apparatus of the present application by merely removing the standard dump body and substituting the apparatus disclosed herein.

By this means the truck has a double utility in that when desired it is used in association with a standard dump body for transporting any material desired and by the removal of the standard dump body for the substitution of the present apparatus the same truck may be used for transporting wet, flowable concrete from a mixing plant to the point where the construction operations are being conducted.

Having described my invention I do not wish to be limited to the specific construction illustrated in the drawings, many modifications thereof falling within the scope of the appended claims, being apparent to those skilled in the art.

I claim:

1. Apparatus for transporting wet, flowable concrete adapted to be mounted on a truck interchangeably with a standard dump body, comprising a frame, a tank carried by said frame, a motor carried by said frame for rotating said tank, a trunnion bearing and a support therefor

disposed between said motor and said tank, said support also having means for supporting one end of the power shaft of the motor.

2. An apparatus of the class described comprising a cylindrical tank, an end wall, a relatively large stiffening plate carried by said end wall interiorly of said tank, a trunnion carried by said end wall, said trunnion having an enlarged head interiorly of the tank, and a flange carried by said trunnion exteriorly of said tank, said head and flange clamping said end wall and stiffening plate.

3. An apparatus of the class described comprising a cylindrical tank shell, an end wall having an annular flange disposed interiorly of said shell and attached to the ends of said shell, said end wall having an opening extending to the end of said wall, an external reinforcing bar attached to said shell adjacent the said opening and extending to the plane of said end wall, a reinforcing frame for said opening affixed to the outer face of said end wall, and a door for said opening.

4. Apparatus for transporting wet, flowable, ready-mixed concrete from a mixing plant to a place of usage comprising, a frame, a pair of spaced trunnion bearings upon the frame, a tank having horizontal trunnions at opposite ends engaged in the trunnion bearings, and an opening between a trunnion and the periphery of the tank in one end of the tank, closable by a closure member; in which each tank end is clamped with a trunnion head, a relatively large diameter stiffening plate which is welded around its periphery to the tank end, and a flange member.

5. Apparatus for transporting wet, flowable, ready-mixed concrete from a mixing plant to a place of usage comprising a frame, a pair of spaced trunnion bearings upon the frame, a tank having horizontal trunnions at opposite ends engaged in the trunnion bearings, and an opening between a trunnion and the periphery of the tank in one end of the tank, closable by a closure member; in which a flange is secured concentric with the trunnion on the outside of the end of the tank having the opening and in which the closure member slides in tapered guides which cause the door to move toward the tank as it slides toward the periphery of the tank and which tapered guides permit the door to move away from the tank as it moves toward the flange, whereby the door clears part of the flange to thus permit a greater distance of opening of the door.
